[57] **CLAIM**

The ornamental design for a structured packing element, as shown and described.

DESCRIPTION

FIG. 1 is a top front perspective view of a structured packing element, showing my new design;

FIG. 2 is an enlarged fragmentary end elevational view of a structured packing element which repeats as best seen in FIG. 1;

FIG. 3 is a top plan view of the structured packing element of FIG. 1;

FIG. 4 is a right side elevational view thereof;

FIG. 5 is a left side elevational view thereof;

FIG. 6 is a bottom plan view thereof;

FIG. 7 is a rear elevational view thereof;

FIG. 8 is a front elevational view thereof; and,

FIG. 9 is a cross sectional view of the structured packing element shown in FIG. 1, taken along line 9—9 in FIGS. 3 and 8.
